UNITED STATES PATENT OFFICE.

GERTRUDE NOTT HOWE, OF NEW YORK, N. Y.

DETACHABLE FIRE-PAN FOR STOVES.

SPECIFICATION forming part of Letters Patent No. 388,976, dated September 4, 1888.

Application filed July 16, 1887. Serial No. 244,512. (No model.)

To all whom it may concern:

Be it known that I, GERTRUDE NOTT HOWE, of the city, county, and State of New York, have invented a certain new and useful Improvement in Detachable Fire-Pans for Stoves, 5 of which the following is a specification.

This invention relates to an improvement in detachable fire pans which are adapted to be set in the top openings of stoves, ranges, and to the like, for building a fire only beneath the vessel to be heated, and thus avoiding the necessity of heating the whole stove or range to the required temperature.

The object of my improvement is to provide 15 a detachable fire-pan of this character, whereby greater simplicity and economy of construction and convenience in use are obtained than is ordinarily possible.

I will first describe in detail a detachable 20 fire-pan for stoves embodying my improvement, and then point out the various features of the improvement in the claim.

Reference is to be had to the accompanying drawings, forming a part of this specification, 25 in which similar letters of reference designate corresponding parts in all the figures.

Figure 1 is a side, partly sectional, elevation of a detachable fire-pan embodying my improvement set in the top opening of a stove, the stove-top being in section. Fig. 2 is a sectional plan of the said fire-pan on the line *x*-*x*, Fig. 1. Fig. 3 is a sectional plan view, similar to Fig. 2, of a modified form of fire-pan embodying my improvement.

The body *A* of the detachable fire-pan may 35 be cylindrical, as shown in Figs. 1 and 2, to fit within a single circular opening, *B*, in the stove or range top *C*, or it may be oblong, as shown in Fig. 3, for reception within the opening left by the removal of the lids *D* covering, and cross-piece *E* separating, adjacent top openings *B*, as indicated in dotted lines 40 therein.

The outwardly-projecting flange *F*, surrounding the top of the body *A*, in each form 45 thereof, I make by bending over the sheet metal of which said body is composed, so that when the flange is seated within the counter-

sunk top opening *B*, to uphold the body of the fire-pan, it will, owing to its thinness, permit 50 the proper lid for the opening or any cooking utensils of any size to be seated therein without necessitating the removal of the fire-pan. The body *A* has the usual lateral openings *H* and perforated bottom *G*, to admit of an 55 ample circulation of air to and about the fire therein and for the ready admission of wood or fuel of greater length than the pan.

For lightness and economy I form the bottom *G* of the fire-pan also of sheet metal, united 60 to the sheet-metal side wall by an ordinary lap and fold or other unsoldered joint, and having the perforations cut or stamped therein, as indicated in Fig. 1.

When the body *A* of the fire-pan is of insufficient depth to maintain the vessel to be heated properly above the fire therein, or a greater draft is desired, an elevated stand, *I*, is employed consisting of a cylindrical rim, *J*, having a flange, *K*, projecting outward from 70 its lower edge and adapted to rest upon the stove or range top *A* around the opening *B* therein. Lateral apertures *L* are formed in the rim *J* near the flange *K*, to permit the passage 75 of air into the fire-pan below the vessel being heated.

Two stands, *I*, may be used with the fire-pan having the oblong body, the cross-piece *E* being placed in its usual seat and bearing upon the body-supporting flange *F*, as before 80 stated, and the stands resting upon said cross-piece and the stove or range top.

Having thus described my invention, I claim as new and desire to secure by Letters Patent—

A detachable fire-pot for stoves, comprising 85 the body portion *A*, having opposite fuel-receiving openings *H*, a flange, *F*, to fit the countersunk stove or range top opening, and a bottom having openings, whereby fuel of greater length than the width of the fire-pot 90 may be used, substantially as set forth.

GERTRUDE NOTT HOWE.
